WIRE WRAPPING MACHINE.

APPLICATION FILED JAN. 18, 1911.

Patented Mar. 19, 1912.

2 SHEETS—SHEET 2.

UNITED STATES PATENT OFFICE.

DONALD ELDER, OF ONEHUNGA, NEW ZEALAND.

WIRE-WRAPPING MACHINE.

1,020,599.

Specification of Letters Patent. Patented Mar. 19, 1912.

Application filed January 18, 1911. Serial No. 603,356.

To all whom it may concern:

Be it known that I, DONALD ELDER, a citizen of the Dominion of New Zealand, and residing at Onehunga, in the Provincial District of Auckland, in the Dominion of New Zealand, have invented certain new and useful Improvements in Wire-Wrapping Machines, of which the following is a specification.

10 The invention provides a machine for binding together two or more wires and is particularly useful for securing wire netting to fencing wires.

According hereto a binding wire is fed by 15 a pair of rollers through a jaw which receives the wires to be bound together. By the turning of a handle a wheel mounted in the jaw, and having a gap which admits the wires to approximately its center, is revolved and a laterally projecting pin caused 20 to engage the binding wire and coil it the desired number of times around the wires to be bound together. A cam-operated cutter is provided to sever the binding wire 25 and after such a wire has been properly coiled about the wires to be bound together the machine is removed to another place and the operation repeated.

I will now describe the details of my invention by the aid of the drawings wherein:

Figure 1 is a plan, Fig. 2, a side elevation, Fig. 3, a part sectional elevation with a wheel removed, Fig. 4, a cross sectional elevation on line 4—4, Fig. 3 showing grooved feed rollers, Figs. 5 to 8 inclusive are side sectional elevations showing part of the apparatus. Figs. 9 and 10 are front end sectional elevations of the gap wheel and parts, 40 and Fig. 11 is a front elevation showing wire netting bound to a wire of a fence. Fig. 12 is a detail plan view of the gap wheel. Fig. 13 is an elevation of said wheel.

The binding wire 1 (see Figs. 1 to 3) is 45 passed through a central hole 2 in the handle 3 and between the feed rollers 4 and 5 journaled in the frame 6 of the machine and having corresponding grooves in their circumferential peripheries to receive it. It 50 then passes through a die 7 and longitudinally through a jaw 8 having a projecting lip 9 by which the wire is directed upwardly. A hand wheel 10 mounted upon a pin 11, fixed in the frame, is revolved by a 55 handle 12 and has a segment of gear teeth which periodically engage with the pinion

13 fixed upon a spindle 14 of feed roller 4 which roller has gear teeth engaging with similar teeth of the feed roller 5. The spindle of the roller 5 is free to move in slots 43 and 44 in the frame. A spring 45 in a recess in the frame bears upon a bracket 5^a, which carries the spindle of the roller 5 (see Fig. 4) to permit said roller to move downward in case sufficiently thick binding wire is used. A bevel wheel 15 upon the side of the wheel 10 is in gear with a bevel pinion 16 upon a spindle 17 revoluble in the frame and having a bevel pinion 18 upon the opposite end gearing with the bevel pinion 19 upon the face of the spur wheel 20 which revolves upon a spindle 21 fixed in the jaw 8 and is in gear with the gap wheel 23 rotatably mounted in the end of a lever 30 afterward referred to. The gap wheel has a gap 25 from its circumference to beyond the center, to receive the wires 26 and 27 which are to be bound together, and the jaw has also a gap 28 to permit the wires to pass axially through the center of the gap wheel. A projecting flange from wheel 10 forms a ring cam 29 which operates a lever 30 pivotally supported upon a pin 31 passing through a stud 32 projecting from the frame. The gap wheel is revolvably mounted on the forward end of the lever so that when the lever is operated by the cam 29 the gap wheel (which has a relatively wide face so that it remains in gear with wheel 20) is moved laterally. The lever is pressed outwardly by a spiral spring 46. A pin 33 projecting eccentrically from the gap wheel has a friction ring 34 adapted, when said wheel is shifted laterally and rotated, to engage with the binding wire 1 and to bend it in a spiral coil around the wires 26 and 27. To said pin 33 is also attached one end of a leaf spring 47 against which said binding wire bears. The wheel 10 has also a cam 35 upon the face opposite to cam 29, and arranged to engage a pin 36 and thereby to operate a lever 36^a pivoted upon a pin 37 in the frame and having a cutter 38 at its end projecting over the face of the die 7 through which the binding wire passes. The lever 36^a is pressed away from the die 7 until operated by the cam, by a spring 40. A projection 41 from wheel 20 is arranged to engage in the gap 25 at each rotation of wheel 20 and to continue the rotation of the gap wheel which would otherwise come to rest through the absence of teeth in the gap.

- In operation the binding wire is pushed through the handle 3 and hand wheel 10 continuously turned by its handle until a binding has been effected the wire 1 being passed by feed rollers through the die 7 until it projects beyond the lip 9 as shown in Figs. 1 and 3. The wires to be bound together are passed through the gap in the jaw and also the gap in the wheel 23 (see Figs. 9 and 10). Cam 29 is timed to operate lever 30 by pressing the rear end thereof outwardly and the gap wheel is moved laterally so that the ring upon the projecting pin 38 engages the binding wire (which is held from one end by the now stationary feed rollers) and bends its forward end in a spiral coil around the wires 26 and 27. The cam 29 is shaped so that the gap wheel gradually returns to its normal position under the influence of spring 46 and the bending of the wire spirally is thereby facilitated. When the binding has been effected the cam engages pin 36 on lever 36^a and the wire is severed by the cutter passing over the face of the die 7. The coiling and cutting of the binding wire is clearly shown in a series of steps in Figs. 5 to 8 while Fig. 9 shows the gap wheel in the position it occupies at the commencement of the coiling, and Fig. 10 when the coiling has been completed. Fig. 11 shows a piece of wire netting 42, the upper wire 26 of which is bound to the fencing wire 27.
- What I do claim and desire to secure by Letters Patent of the United States is:—
1. A machine for the purpose indicated, comprising in combination a frame, a handle thereon, a pair of geared feed rollers, a pinion connected to one of said rollers, a hand wheel having a segment of teeth engaging said pinion, means for revolving the hand wheel, a lever, a cutter at one end thereof, a cam for operating the lever, a die through which the binding wire passes, a jaw in the frame, a gap wheel having gear teeth, a pin projecting from the gap wheel, a pinion in gear with the gap wheel, a tooth wheel upon said hand wheel, gears for driving the pinion therefrom, a lever on which the gap wheel is rotatably mounted, and a ring cam upon the face of the hand wheel for operating said lever, substantially as specified.
  2. In a machine for the purpose indicated, the means for coiling the binding wire comprising in combination the gap wheel, a pin projecting laterally therefrom, a pinion in gear with the gap wheel, a projection from the pinion adapted to engage the gap in the gap wheel, means for rotating the pinion, a lever on which the gap

wheel is rotatably mounted, a ring cam operating said lever, with means for rotating said cam, substantially as specified.

3. In a machine for the purpose described, the combination with means for feeding a binding wire, of means for coiling such wire around the wires to be bound together, and a cutter for severing the binding wire. 70

4. In a machine for the purpose described, the combination of a support for two wires, means for feeding a binding wire transversely of the first said wires, means for coiling the binding wire about the first 75 said wires, and a hand device for actuating both said feeding and coiling means.

5. In a machine for the purpose described, the combination of means for engaging two wires to be bound together, 80 means for supporting a binding wire and feeding the same longitudinally, means for coiling the binding wire about the first said wires, a cutter for severing the binding wire, and a driving wheel adapted to actuate 85 the feeding, coiling and cutting means.

6. In a machine for binding together two or more wires, the combination of a coiling wheel having a radial gap adapted to receive the wires to be bound together, means 90 for feeding a binding wire, means for coiling such wire about the first said wires, and a common driving mechanism for actuating both said feeding and coiling means.

7. In a machine for binding together two or more wires, the combination of a coiling wheel having a radial gap to receive the wires to be bound together, means for feeding a binding wire, means for coiling the binding wire about the first said wires, said 100 coiling wheel being supported to move in the direction of the length of its axis during the formation of a coil, and means for actuating the feeding and coiling devices.

8. In a machine for binding together two or more wires, the combination of a coiling wheel having a radial gap to receive the wires to be bound together and provided with a laterally extending eccentric pin at one side of said gap, means for feeding a 110 binding wire into position to be engaged by said pin whereby the binding wire will be coiled about the first said wires as the wheel rotates, and means for actuating said feeding and coiling devices. 115

In testimony whereof I have signed my name to this specification in the presence of two witnesses.

DONALD ELDER.
